UNITED STATES PATENT OFFICE

JACOBUS BOERSTRA, OF HAARLEM, NETHERLANDS, ASSIGNOR TO THE BABCOCK & WILCOX COMPANY, OF BAYONNE, NEW JERSEY, A CORPORATION OF NEW JERSEY

AIR HEATER

Application filed January 13, 1927, Serial No. 160,816, and in Great Britain May 10, 1926.

This invention relates to an air heater that is especially adapted to be heated by hot waste gases from a boiler furnace, and will be understood from the description in connection with the accompanying drawings, in which Fig. 1 is a vertical section through an illustrative embodiment of the device; Fig. 2 is a vertical section on an enlarged scale showing one of the details; Fig. 3 is a section 5 along the line 3—3 of Fig. 1; Fig. 4 is a vertical section similar to Fig. 1 showing a modification; Fig. 5 is a vertical section on an enlarged scale showing details of the modification; Fig. 6 is a section along the lines 6—6 10 of Fig. 5; Fig. 7 is a vertical section through another modification and Fig. 8 is a section 15 along the line 8—8 of Fig. 7.

In the drawings, reference character 1 indicates inclined tubes of a water tube boiler, 20 over which hot gases from the boiler furnace pass, as indicated by the arrow. The hot waste gases after passing from the tubes 1 pass into the air heater through inner tubes 2 that are expanded into tube plates 3 and 4. 25 The tubes 2 are surrounded by and are coaxial with larger tubes 5, so that spaces are left between the inner and outer tubes. The tubes 2 and 5 are preferably made circular in cross section, but may be made of other 30 shapes. The outer tubes 5 are provided near their lower ends with beads 6 that enable the tubes to rest upon the tube plate 7 with the ends of the tubes extending through holes in this plate. The upper or inlet ends of the 35 tubes 5 are made rectangular and expanded sufficiently to fill the air heater, as most clearly indicated in Fig. 3, with the sides of the expanded or enlarged portions 8 of adjacent tubes contacting with each other. The 40 tubes 2 extend beyond the tubes 5 at both ends.

A chamber at the upper ends of the tubes 2 is made up of the tube plate 4 and the walls 9 from which chamber a conduit 10 leads to 45 a stack, or the like. A chamber is also provided below the lower ends of the tubes 5, being made up of the tube plates 3 and 7 and the edge plates 11, from which chamber a conduit 12 leads to the furnace. Air enters 50 the spaces between the upper ends of the

tubes 5 and the outside surfaces of the tubes 2 and passes downwardly along the annular spaces between the tubes into the lower compartment, and thence through the conduit 12 to the furnace while hot gases enter the lower ends of the tubes 2 and pass from the upper compartment through the conduit 10 to the stack. 55

In the modification shown in Figs. 4, 5 and 6 hot gases are passed around the outside of the outer tubes, as well as through the inner tubes, so that the air is heated on both the inner and outer surfaces of the annular streams of air. In this modification, the outer tubes 5' are shown as expanded into an upper tube plate 15, which structure may be, of course, used with the other embodiment shown in Fig. 1, and the tubes 5 shown in Fig. 1 may be installed as shown in the modification, Fig. 4. In the modification shown 60 in Fig. 4, the gas passage above the last pass of the tubes 1 is enlarged so as to provide a space 17 along the side of the air heater. A damper 18 is provided to close or open the passage to the space. When the damper 18 is open a portion of the hot gases pass into the space 17 and then across the outside of the tubes 5', being directed across the tubes, as shown by arrows in Fig. 6, and around the baffle 19, and thence they pass upwardly 65 through the outlet 10 to the stack after having joined the hot gases that pass through the inner tubes 2. Thus the air entering the annular spaces between the tubes 2 and 5' is heated from both sides. 70

In the modification shown in Figs. 7 and 8, the hot waste gases pass from the boiler tubes through the gas passage 16'. Openings are provided from this gas passage or conduit 16', so that the hot gases may pass either 75 through the inner tubes or around the outer tubes or both. A damper 21 is provided for controlling the passage of the gases to the inner tubes and a damper 22 is provided for controlling the passages of the gases around the outer tubes, and a damper 23 is provided so that the gases may be bypassed instead of passing through the air heater. An outlet damper 24 is provided for the gases passing 80 around the tubes and an outlet damper 25 85

is provided for gases passing through the inner tubes.

In the modification shown in Figs. 7 and 8, the inner tubes 26 are expanded into the tube plate 27 at their exit ends and are enlarged at their entrance ends, as shown at 28, into conical shape and are expanded into the plate 29. The outer tubes 30 extend between tube plates 31 and 32 and the enlarged ends 28 of the inner tubes 26 are made of sufficient size to permit the outer tubes 30 to be inserted through the tube plate 29. Air enters through the inlet 33 between the tube plates 27 and 32 and passes through the annular spaces between the tubes into the chamber between the tube plates 29 and 31, thence out through the exit 34 to the furnace, while hot gases pass either through the inner tubes or around the outer tubes or both, thence from the exit conduit 35 to the stack. The entire arrangement is disposed in a chamber adjacent the conduit, as plainly shown, access to this chamber from the flue being had by means of the dampers 21, 22, 24 and 25, and air being admitted and discharged at 33 and 34 respectively.

I claim:

1. In an air heater, coaxial tubes, means for directing hot gases through one set of said tubes, and means for directing air through the other set, the inner tubes extending beyond the outer tubes and ends thereof being enlarged to at least the outer dimensions of the outer tubes.
2. In an air heater, coaxial inner and outer tubes and means whereby hot gases may be passed through the inner tubes, or around the outer tubes, or through the inner tubes and around the outer tubes, at will.
3. In an air heater, a set of parallel tubes, a second set of tubes disposed within those of the first set, an air inlet and outlet connected respectively to the opposite ends of the tubes in the first set, a hot gas inlet and outlet connected respectively to opposite ends of the tubes in the second set, connections from said gas inlet and outlet respectively to the spaces between the tubes in said first set, and valves controlling the flow through each of said connections.
4. In an air heater, a set of parallel tubes, a second set of tubes disposed within those of the first set, an air inlet and outlet connected respectively to the opposite ends of the tubes in the first set, a hot gas inlet and outlet connected respectively to opposite ends of the tubes in the second set, connections from said gas inlet and outlet respectively to the spaces between the tubes in said first set, valves controlling the flow through each of said connections, a by-pass connecting said hot gas inlet directly to said hot gas outlet, and a valve controlling said by-pass.
